UNITED STATES PATENT OFFICE.

ARTHUR L. SMITH, OF CHELSEA, MASSACHUSETTS, ASSIGNOR TO THE A. L. SMITH IRON WORKS, OF CHELSEA, MASSACHUSETTS, A CORPORATION OF MASSACHUSETTS.

COLUMN CAP.

Application filed December 19, 1921. Serial No. 523,294.

To all whom it may concern:

Be it known that I, ARTHUR L. SMITH, a citizen of the United States of America, and resident of Chelsea, in the county of Suffolk and State of Massachusetts, have invented new and useful Improvements in Column Caps, of which the following is a specification.

This invention concerns column caps and relates more particularly to a cap which may be formed from standard structural steel shapes, and to a method of making such caps. One object of the invention is to provide a mode of constructing such caps in a simple and expeditious manner and which is equally applicable to the formation of three or fourway caps.

20 A further object is to provide a novel form of cap embodying brace members integral with the supporting elements of the cap and so arranged as to enable the cap to sustain heavy and eccentrically placed loads without substantial distortion.

In the accompanying drawings there is
25 illustrated by way of example a preferred
arrangement whereby the above objects may
be attained and in such drawings.—

Fig. 1 is a top plan view of a column having a cap embodying the present invention applied thereto, a portion of the cap being broken away.

Fig. 2 is a side elevation of the parts shown in Fig. 1, the lower portion of the column being broken away;

35 Fig. 3 is a view similar to Fig. 1 illustrating a modified form of column cap;

Fig. 4 is a side elevation of the device shown in Fig. 3;

Fig. 5 is a top plan view, partly broken away illustrating a modified form of column cap;

Fig. 6 is a side elevation of the device shown in Fig. 5;

Fig. 7 is a plan view of a still further modification; Fig. 8 is a side elevation thereof;

Fig. 9 is a side elevation illustrating the upper end of a column suitable for the ap-

upper end of a column suitable for the application of the cap of the present invention; and

Fig. 10 is a perspective view of a blank suitable for use in making a column cap in accordance with the present invention.

PATENT OFFICE.

HUSETTS, ASSIGNOR TO THE A. L. SMITH
H. H. SMITH & CO., A CORPORATION OF MASSACHUSETTS.

9, 1921. Serial No. 523,294.

The present invention relates more partic-

ularly to column caps of the general type shown in Patent No. 1,324,976 granted December 9, 1919, to Arthur L. Smith to which reference may be had for a more complete description of certain features thereof.

Referring to Fig. 9, the upper end of a hollow tubular column 1 is shown, such column being adapted to be filled with concrete as indicated at 2, Fig. 2. The upper end of the column is provided with a plurality of radial slots therein being shown as having a pair of axial diametrically extending slots 3, 4 respectively, arranged at right angles to each other, and at

Referring to Fig. 10, a section of angle iron is indicated at 5, this section being cut to a length substantially equal to the desired width of the column cap. This angle iron comprises a pair of flanges 6, 7, shown as of substantially equal width, it being understood however that an angle iron having unequal flanges might be employed if desired. 75

At the central part of one of the flanges, herein indicated as flange 6, a triangular section 8 is cut out as indicated by the broken lines. As herein shown, this section is of right triangular form, the right angle 9 thereof being directed inwardly and being included between the sides 10, 11 of the triangle. The apex of the right angle, indicated at 12, lies substantially in the plane of the inner face of the flange 7. Preferably, the corners of flange 7 are also cut off as indicated by the diagonal, broken lines 7^a 7^b.

After the removal of the triangular section 8 and the corner portions of flange 7, the angle iron is bent about the central line 13 of the flange 7, whereby to cause the edges 10, 11 to be brought substantially into contact. The bending of the iron in this fashion results in the formation of a three walled bracket, the end portions 14, 15 of the flange 6 together constituting one wall, while the end portions 17, 18 of the flange 7 constitute respectively the other walls. The three walls of the bracket as thus constructed lie in planes perpendicular to each other, and the bracket is preferably so disposed in forming the column cap that the walls 17, 18 thereof are vertical, forming integral brace members, while the wall com-

prising the members 14, 15, and which forms the support element of the bracket, is horizontal, such wall having the diagonal slit 19 therein as indicated in Fig. 1. As will be noted in the latter figure, the horizontal wall of this bracket has a rectangular recess 20 at its outer corner, such recess resulting from the fact that the triangular piece 8 removed from the flange 6 is of less length at its outer edge than said flange. If it be desired to eliminate such recess, however, this may be done by cutting the angle iron 5 along lines such as indicated at 21, 22, Fig. 10, so that the length thereof coincides with the length of the outer edge of the triangular section removed. The shape of the horizontal surface of such a bracket is indicated by the broken lines 23, 24, in Fig. 1.

After the cutting and bending of the angle irons to form the three wall brackets, a plurality of such brackets are assembled with their horizontal surfaces lying in the same plane, and the vertical walls of adjacent brackets are then secured together as by means of rivets 25 as indicated in Fig. 1. In the latter figure four such brackets are shown as having been secured together, the horizontal surfaces of the several brackets thus constituting a figure of generally square outline. The composite structure thus formed is now arranged in the slots 3, 4 at the upper end of the column, the contacting vertical walls of adjacent brackets being seated within the radially extending slots. The cap thus formed may if desired be used without further modification, but it is preferred to secure to the horizontal supporting surfaces of the bracket members a plate such as 26, which extends over the several brackets, and forms the immediate support for the beam or girders.

As shown in Fig. 1 this plate may be square and of a size to overlap and cover the recesses 20 if such be formed in the outer corners of the several brackets. The cap thus constructed is symmetrical with respect to the axis of the column and is well adapted for supporting the ends of four beams or girders, or for supporting a single continuous girder extending transversely across it, and the ends of two abutting girders.

In the arrangement shown in Figs. 3 and 4 a pair of the three walled brackets such as hereinbefore described are connected together by the rivets 25^a, the connected vertical walls 18, 17^a of such brackets being seated within a radial slot in the top of the column. In this case, however, instead of connecting a second pair of similar brackets to the first named pair of brackets, an angle iron comprising the vertical flange 27 is secured to the flanges 17, 18^a of the

aforesaid pair of brackets, such flange being connected thereto by means of rivets 28, the other flange such as 29 of the angle iron extending in a horizontal plane and in alignment within the walls 14 of the pair of three walled brackets. The cap thus formed is unsymmetrical with respect to the axis of the post and is adapted to support the ends of three beams or girders abutting at the axis of the post or a single continuous girder having the end of a beam abutting one side thereof. If desired this type of column cap may also be provided with a supporting plate 30 resting upon the walls 14 and the flange 29.

In the form of device shown in Fig. 5 a column cap is formed substantially as shown in Fig. 3 comprising the three walled brackets having the vertical walls 17^a, 18 secured together by rivets such as 31 and the walls 17 and 18^a being riveted to the depending flange 32 of an angle iron having the horizontal flange 33. In this case, however, there is secured to the flange 32 of the angle iron the cross bar 34 of a T iron comprising the vertically disposed web 35. The latter member is received within a slot in the top of the post and serves as a brace or support for the flange 33.

In Fig. 7 the upper end of the post is shown as having a T iron comprising the web 36 extending transversely across the end of the post and seated within a diametral slot therein, such iron also comprising the horizontal flange 37. In this case the flange 37 is unsymmetrical with respect to the member 36, and associated with the longer portion thereof is a T iron comprising the web 38 and the cross bar 39, the latter being connected by means of rivets 40 to the flange 36. The member 38 thus serves to support the unsymmetrical overhanging portion of the T iron whereby to strengthen that portion of the cap upon which the greater part of the weight will rest. Supporting plates 41 and 42 respectively may be associated with the caps shown in Figs 5 and 6, 7 and 8 respectively if desired.

While as herein illustrated the column has been shown as provided with slots arranged to intersect at right angles with each other, it is to be understood that the slot might be arranged in planes intersecting at other angles if desired, and that in such case the bracket members employed would be so cut and bent as to provide wall members adapted when secured together to fit within such slots.

It is also to be understood that various changes and modifications in the shape and relative dimensions of parts might well be made without departing from the spirit of the present invention.

Having thus described the invention, to

gether with the mode of use thereof, what I claim and desire to secure by Letters Patent of the United States is:

1. A column cap comprising a plurality of three walled brackets formed from structural iron and arranged with one wall of each bracket in contact with a wall of the other, and with the third wall of each of said brackets lying in a common plane, and means for securing together said contacting walls.
2. In combination with a column provided with a pair of diametral slots extending at right angles to one another, a column cap comprising a pair of three walled brackets formed from structural iron, one wall of each of said brackets being disposed in contacting relation within one of said slots, a second wall of each of said brackets being disposed within another of said slots, the third wall of each of said brackets lying in a common plane.
3. In combination with a column having a plurality of radially extending slots in its end, a column cap comprising a plurality of like brackets, each having three walls, two of said walls being vertically disposed, and the other being horizontal, and means securing a vertical wall of one bracket to a vertical wall of another, such connected pair of walls being disposed within one of said radial slots in the column.
4. In combination with a column having a diametral slot and an intersecting radial

slot in its end, a column cap comprising a pair of three walled brackets each having a vertical wall disposed in said radial slot and in contact with one another, and each having a second vertical wall disposed in said diametral slot, said last named walls being in alignment, and an angle iron having one flange also disposed in said diametral slot and having its other flange lying in the plane of the third walls of said brackets.

5. In combination with a column provided with a pair of axial slots in its end, a pair of three walled brackets, a wall of each bracket being disposed in contacting relation within one of said slots and a second wall of each bracket being disposed in alignment in the other of said slots, a plate like element also disposed in the latter of said slots and secured to the aligned walls of said brackets, and a T-shaped member having its cross-bar secured to said plate like element and its other member arranged with in said first named slot.

6. A column cap comprising a plurality of three walled brackets, each comprising a horizontal wall and two vertical walls, means for securing a vertical arm of one bracket to the adjacent wall of another bracket, and a plate contacting with and secured to the horizontal walls of the several brackets.

Signed by me at Boston, Massachusetts, this sixteenth day of December, 1921.

ARTHUR L. SMITH.

Certificate of Correction.

It is hereby certified that in Letters Patent No. 1,501,194, granted July 15, 1924, upon the application of Arthur L. Smith, of Chelsea, Massachusetts, for an improvement in "Column Caps," errors appear in the printed specification requiring correction as follows: Page 1, line 56, for "No. 1,324,976" read *No. 1,324,076*; page 2, line 42, for the word "beam" read *beams*; and that the said Letters Patent should be read with these corrections therein that the same may conform to the record of the case in the Patent Office.

Signed and sealed this 19th day of August, A. D. 1924.

[SEAL.]

KARL FENNING,
Acting Commissioner of Patents.
